UNITED STATES PATENT OFFICE.

SIDNEY SMITH, OF MANSFIELD, OHIO, ASSIGNOR TO THE BARNES MANUFACTURING COMPANY, OF MANSFIELD, OHIO, A CORPORATION OF OHIO.

SPRAYING-PUMP.

1,091,401.

Specification of Letters Patent.

Patented Mar. 24, 1914.

Application filed September 29, 1911. Serial No. 651,980.

To all whom it may concern:

Be it known that I, SIDNEY SMITH, a citizen of the United States, residing at Mansfield, in the county of Richland and State of Ohio, have invented certain new and useful Improvements in Spraying-Pumps, of which the following is a specification.

This invention relates to pumps used in spraying vegetation for destroying injurious insects and fungus growths, and has for its object the provision of a pump which may be secured firmly upon either the side or the end of a barrel and in which the parts will be easily accessible for cleaning or repairing or to permit the removal of an obstruction.

A pump embodying the invention is illustrated in the accompanying drawing and will be hereinafter fully described, the novel features of the invention being particularly pointed out in the appended claims.

In the drawings, Figure 1 is partly a side elevation and partly a central vertical section of the complete pump. Fig. 2 is a plan view of the support. Fig. 3 is a side elevation of the support. Fig. 4 is a bottom plan view of the support. Fig. 5 is a transverse section of the support taken on the line 5—5 of Fig. 3. Figs. 6 and 7 are enlarged detail views of the valves.

The pump comprises a plunger casing or cylinder 1 and a barrel or air chamber 2 which are secured upon and rise from a common base 3. This base 3 is a hollow casting having annular flanges 4 and 5 on its upper side, the bore of the flange 4 being unobstructed while the flange 5 is bridged by a partition 6 as shown clearly in Fig. 1. Both flanges 4 and 5 are internally threaded and the lower end of the plunger casing is threaded so as to directly engage the threads of the flange 4 and be thereby secured in position. A bushing 7 is threaded into the flange 5 and the lower end of the cylinder 2 is threaded onto said bushing and is thereby supported and prevented from collapsing. The upper end of the cylinder 2 is closed by a cap 8 having a nipple or elbow 9 formed on its upper side, the inner end of said nipple being engaged by a discharge tube 10 which depends from the cap within the air chamber and terminates at or near the bottom of said chamber. In the outer end of the elbow or nipple is secured a coupling or union 11 to which is attached the hose by which the liquid is directed onto

the plants. On the upper side of the nipple 9 is a lug or post 12 upon which the handle or operating lever 13 is fulcrumed. To the said lever are pivoted the upper ends of the plunger rod 14 and the agitator rod 15, the former passing into the casing 1 and the latter extending below the casing and playing through a guide 16 on the end of the base 3. The agitator 17 is a flat plate secured on the lower end of the rod 15 and a stop pin 18 is provided on the rod which, by impinging against the base 3, limits the upward movement of the lever and, consequently, prevents the lever being raised so far as to withdraw the plunger from the casing 1. The plunger consists of an upper member 19, to which the plunger rod 14 is pivoted, and a lower member 20 threaded upon the upper member, the members being so shaped as to secure the packing 21 and compress the same against the wall of the plunger casing so as to prevent leakage.

In the base 3, are secured two valve casings 22 and 23 which are arranged concentric with the flanges 4 and 5, respectively. The casing 22 comprises a hollow body 24 having an externally threaded intermediate portion 25 adapted to engage a threaded opening in the bottom of the base and thereby secure the casing in place while immediately below said threaded portion the body is formed with an annular shoulder 26, adapted to engage the under surface of the base 3 and thereby prevent the casing being turned into the base so far as to interfere with the free flow of the liquid or to be liable to injury through contact with the plunger. The upper end of the body 24 is reduced and threaded, as shown at 27, and this threaded reduced end is engaged by a spider or cage 28 which confines a ball valve 29 adapted to seat upon the upper end of the body, as will be readily understood. It will be seen that the casing may be screwed into or out of the base without disturbing the plunger or the valve casing 23 and that by merely unscrewing the cage or spider the ball 29 will be freed so that its seat may be cleaned or a new ball substituted or other necessary attention given. The lower end of the body 24 is open and internally threaded to receive and secure the upper end of the suction pipe 30, the lower end of said pipe being equipped with a strainer 31, as shown. It may be noted that while the agitator is disposed close to the suction pipe,

the lower end of the pipe is arranged below the limit of movement of the agitator so that, while the liquid will be thoroughly agitated, the heavy constituents of the same 5 will not be drawn into the pump to clog its action.

The valve casing 23 is similar to the casing 22, having a reduced upper end upon which is screwed a cage or spider 32 to confine a ball valve 33 which seats on the upper end of the body. The body is also provided with an intermediate externally threaded portion 34 by which it is secured in the base 3 but its lower end is closed and between said lower end and said threaded portion 34 are ports 35, the annular shoulder 36 adapted to bear against the bottom of the base being located below said ports. This casing extends through and fits snugly in a smooth-bored opening in the bottom of the base while the threads 34 engage a threaded opening in the partition 6, as shown in Fig. 1, the ports 35 being thus brought into alignment with the passage 37 in the base.

To support the pump upon the tank or barrel, a bracket or shelf 38 is employed, said bracket or shelf having a flat top in which is formed a large opening 39 to accommodate the several working parts. At the corners of the shelf are openings 40 through which fastenings screws or bolts may be inserted to secure the device in place and along the side edges of the shelf are depending flanges 41 having arcuate lower edges to fit the side of the barrel. Inwardly from but adjacent the flanges 41, longitudinal ribs or flanges 42 are formed on the underside of the shelf, said ribs having straight lower edges parallel with the top of the shelf and adapted to rest upon a flat surface so that the pump may be supported on the end of the tank or barrel, it being understood, of course, that when the device is placed on the side of the barrel said ribs 42 will pass into the opening in the barrel. The pump is secured to the shelf by a pair of clamping jaws or plates 43 which are adapted at one end to engage under hooks or overhanging lips 44 on the shelf and near the opposite end are provided with notches 45 through which set screws 46 are inserted into threaded openings 47 in the shelf to secure the clamping plates. In the inner edges of the clamping plates are opposed approximately semi-circular recesses 48 adapted to receive the pump barrel or cylinder 2, extended ribs or flanges 49 being formed around said recesses to constitute a split sleeve whereby the cylinder may be firmly clamped without injury. The greater portion of the inner edges of the clamping plates are straight so that, when the plates are in

position around the pump cylinder, they will be parallel and spaced apart to provide working room for the plunger and 65 agitator rods. Ribs or flanges 50 are formed on the upper sides of the clamping plates along the inner edges of the same and bolts 51 are fitted in the ends of the said ribs or flanges in order that the plates may be 70 drawn firmly around the pump cylinder. The ribs or flanges reinforce the clamping plates so as to prevent buckling of the same and also constitutes guides to prevent lateral swaying and bending of the plunger and 75 agitator rods. The shelf and the clamping plates may be disposed at any point along the pump cylinder so as to adapt the pump to the depth of the barrel or tank upon which it is placed.

The operation will be readily understood. On the up stroke of the plunger a partial vacuum will be formed below the same which will cause the valve 29 to rise and the valve 33 to drop whereupon the liquid will flow 85 into the base 3. On the down stroke of the plunger, the valves will be reversed and the liquid will be forced through the ports 35 and past the valve 33 into the cylinder 2. The accumulation of liquid in the cylinder 90 2 will compress the air therein with the result that the liquid will be forced into and through the discharge pipe in a steady stream.

Having thus described my invention, what 95 I claim is:

1. In a pump, the combination with a cylinder, of a shelf adapted to be secured upon a receptacle and through which the cylinder passes, and clamping jaws detachably secured on the upper side of said shelf and embracing the cylinder.

2. In a pump, the combination with a cylinder, of a shelf through which the cylinder passes provided on its under side with 105 depending flanges having arcuate lower edges and with other flanges having straight lower edges, and clamping jaws secured on said shelf and embracing the cylinder.

3. In a pump, the combination of a cylinder, a shelf through which the cylinder passes, overhanging lips on the shelf near one end thereof, clamping jaws embracing the cylinder adapted at one end to engage under said overhanging lips and having 110 notches in their edges at the opposite end, and set screws inserted through said notches into the shelf.

In testimony whereof I affix my signature, in presence of two witnesses.

SIDNEY SMITH.
